(57) **CLAIM**

The ornamental design for a double tail light module, as shown and described.

DESCRIPTION

FIG. 1 is a perspective view of an embodiment of a double tail light module showing my new design in an assembled state as seen from the top, front, and right side thereof;

FIG. 2 is a front plan view thereof;

FIG. 3 is a rear plan view thereof;

FIG. 4 is a right side elevational view therefore, the left side elevational view being a mirror image of the right side elevational view;

FIG. 5 is a bottom plan view thereof; and,

FIG. 6 is a top plan view thereof.

The broken lines in FIGS. 1, 2, 3, 4, 5, and 6 are used for illustrative purposes only and form no part of the claimed design.
